UNITED STATES PATENT OFFICE

MAYNARD A. LASWELL, OF LOS ANGELES, CALIFORNIA

CONTROL FOR FIRE EXTINGUISHING APPARATUS

Application filed April 16, 1933. Serial No. 355,492.

This invention has to do with a control for fire-extinguishing apparatus, and it is a general object of the invention to provide an effective, dependable, and commercially practical control for a plurality of units of fire-extinguishing apparatus whereby the units of apparatus may be operated or set into operation successively with suitable time intervals between operations.

10 Certain gases, for example, carbon dioxide gas, have been found effective in extinguishing fires and in preventing fires where parts become overheated. It has been found that an atmosphere containing a certain percentage of carbon dioxide gas will not support combustion, even though temperatures may be high. It is therefore desirable in controlling fire by carbon dioxide gas to establish an atmosphere containing sufficient 15 carbon dioxide gas to prevent combustion and to maintain such atmosphere until such time as the dangers of fire have been eliminated.

It is an object of the present invention to 20 provide apparatus whereby carbon dioxide gas or other fire extinguishing gas may be discharged in such manner or in such quantity as to extinguish or prevent a fire and to thereafter, at suitable, timed intervals, discharge further amounts of gas so that fire 25 will not recur or start.

It is an object of this invention to provide apparatus of the character mentioned which is automatic in operation and which will dependably control a plurality of units of fire extinguishing apparatus so that a fire can be extinguished and/or controlled wholly without manual operation.

It is another object of the invention to 30 provide apparatus of the character mentioned with various control features whereby it is automatically put into operation and is automatically taken out of operation when certain predetermined conditions exist. For 35 instance, the apparatus may be put into operation through thermally-controlled means and may be taken out of operation after a predetermined number of units have been discharged.

The various objects and features of my in-

vention will be best and more fully understood from the following detailed description of a typical form and application of the invention, throughout which description reference is had to the accompanying drawings, in which:

Fig. 1 is a view illustrating the principal working parts of the apparatus provided by this invention. Fig. 2 is an enlarged detailed sectional view taken as indicated by line 2—2 on Fig. 1. Fig. 3 is an enlarged detailed sectional view taken as indicated by line 3—3 on Fig. 1. Fig. 4 is a diagrammatic view illustrating the present invention being a view illustrating a typical electrical circuit embodying the invention. Fig. 5 is a detail view of parts in the relay. Fig. 6 is a diagrammatic view illustrating the apparatus connected with an area or space to be protected. Fig. 7 is a view of the upper portion of a container and control head.

The present invention is in the nature of a control for fire-extinguishing apparatus and may be embodied in various forms and may be used in various situations. The invention 75 is particularly applicable to the control of gas, say, for instance, carbon dioxide gas, and, as it has been successfully used in the control of carbon dioxide gas, I will confine this disclosure to such application. It is to be 80 understood that the broader principles of the invention are not to be construed as limited to the details herein set forth.

The apparatus or system provided by the present invention is intended primarily to 85 control a plurality of fire-extinguishing units, for instance, a plurality of units of carbon dioxide gas. Each unit to be controlled may include one or more containers 10 of gas equipped with control heads whereby they 90 can be actuated electrically. The gas is usually sealed in the containers under high pressure at which it is normally in the liquid state. The control heads 11 applied to the containers 10 may be of any construction operable electrically to open the containers. For purpose of example, I will refer to the patent to Johann issued May 29, 1928, Number 1,671,368, entitled Electro-magnetic control for fluid containers, as disclosing one con-

struction that may be used in the heads 11. In the particular arrangement illustrated the first unit of fire-extinguishing apparatus includes a plurality of containers 10, while the other, or following units, each comprise but one container 10. It will be obvious that any desired number of containers can be included in each unit. It is to be understood, of course, that the units of fire-extinguishing apparatus 10 may be suitably connected with conduits 10^a operable to deliver the gas to the desired point or points, say, for example, to a space or chamber 10^b. The space 10^b is illustrated diagrammatically as a room, the walls 10^c of which are provided with openings such as doors and windows 10^d.

The control provided by this invention includes, generally, a timer T controlling the energization of the fire-extinguishing units 20 from a power circuit carried by lines L, control means C for starting operation of the timer, that is, for starting operation of the actuating motor M of the timer, means A for automatically stopping operations of the 25 timer after a predetermined operation, means B for de-energizing the circuit through the control means C after a predetermined operation of the timer, and various other features and details, the functions of which will be 30 hereinafter described:

In the preferred form of the invention the main power lines L are connected with the apparatus through a main control switch S. One of the main lines L is connected through 35 the switch S and a suitable connection 12 with a buss bar 13 in the timer. The other line L is connected with spaced contacts 14 in the timer through a connection 15, a releasing switch 15^a, a connection 15^b, the control means C, a connection 16, the heads 11 controlling the fire-extinguishing units and connections 17 extending between the heads of the fire-extinguishing units to the several contacts 14.

45 The timer T includes the buss bar 13, contacts 14, and motor M, above referred to, and is operable to successively connect the contacts 14 and the buss bar 13 to successively 50 actuate the units of fire-extinguishing apparatus. The timer may be of any suitable type or design and may include various features of construction. In the case shown the timer includes contacts 18 for making connection between the contacts 14 and the buss 55 bar 13 and a contact actuator 30 operable by a screw 19 to successively actuate the contacts 18. The screw 19 is supported by a pair of end plates 20 and is adapted to be operated by the motor M through a suitable 60 drive. For ordinary installations it is desirable to have a considerable time interval between the operation of each unit of fire-extinguishing apparatus, and therefore it is preferred to have the screw 19 operate slowly. It is an object of the invention to main-

tain a fire-extinguishing atmosphere in the space 10^b during operation of the apparatus. In any particular case the timer T is set to operate the control heads 11 one after the other at such intervals as to compensate for leakage of gas such as occurs at the doors or windows 10^d or other such parts. To meet these conditions the drive between the motor M and the screw 19 may include a worm 21 on the motor shaft drive, and a worm wheel 22 mounted on a countershaft 23. A pinion 24 is mounted on the countershaft and drives a gear 25 fixed on the screw 19.

The contact actuator 30 is carried by a block 26 which carries a nut 27 through which the screw 19 operates. The block 26 is held against rotation by a guide rod 28 extending between the end plates 20. Each contact 18 is insulated from the other electrical parts and is carried by spring arms 31 so that it can be moved to simultaneously engage a contact 14 and a contact 32 on the buss bar 13. The contact actuator 30 is carried by the block 26 so that it operates the contacts 18 into engagement with the contacts 14 and 32 in the manner just described. Further, the contact actuator 30 is normally set to hold the first contact 18 in position to close the circuit through the contact 14 of the first fire-extinguishing unit, as shown throughout the drawings, so that the circuit through the heads 11 of the first fire-extinguishing unit is closed upon actuation of the control means C, the switch 15^a being normally closed.

The control means C operates to control the circuit through the timer T and the units of fire-extinguishing apparatus. In practice the control means may be advantageously connected between the connections 15 and 16. In the drawings I have shown the control means C including a manually operable switch 36 and a thermostatic switch 37. The switches are connected between the connections 15 and 16 so that either one completes the circuit upon being closed.

The motor M of the timer is connected with the power lines L so that it is under control of the means C through a relay R. In the arrangement illustrated a connection 40 connects between one of the lines L and one terminal of the motor M. The other line L is connected with the other terminal of the motor through a connection 41, relay R, and a connection 42 extending from the relay to the motor terminal. The connections 41 and 42 extend to spaced terminals or contacts in the relay. The relay has a movable contact 41^a operable to close the circuit between the terminals.

The relay R is under control of the means C so that it operates to close the motor circuit when one of the switches of the control means C is closed. In the arrangement illustrated

the relay R has a winding W with one terminal connected with one of the lines L through a connection 45 and the other terminal connected with the other line L through a connection 46, a release switch 47, and the control means C. In the arrangement shown the release switch 47, which is embodied in the timer, is connected in series in the connection 46. The connection 46 connects with the connection 16 so that the circuit is completed through the means C and the connection 15^b, the switch 15^a, and connection 15. The release switch 47 is normally closed so that the winding W is energized upon either of the switches of the means C being closed.

The means provided for automatically stopping operation of the timer after a predetermined operation includes a control switch 50 arranged in the timer to control the circuit of a release winding 51 in the relay. The release winding 51 has one terminal connected with one line L by a connection 45^a and has the other terminal connected with the other line L through a connection 52 and the switch 50. When the winding 51 is energized, the relay is opened so that the contact 41^a is moved to open the motor circuit.

The switches 47 and 50 above described are embodied in the timer, the switch 47 being normally closed and the switch 50 being normally open. The switches have movable parts or contacts adapted to be operated by the contact actuator 30 of the timer. The parts are related so that the contact actuator closes the switch 50 at the same time that it opens the switch 47. Closing of the switch 47 energizes the winding 51 so that the relay is opened, while the opening of the switch 47 opens the circuit through the winding W of the relay. With this arrangement, it will be apparent that the apparatus is automatically stopped or cut out of operation after a predetermined operation, for instance, after a predetermined number of fire-extinguishing units have been operated or released.

It is to be understood, of course, that the wiring system above described and illustrated in the diagram Fig. 4 is given merely to facilitate an understanding of a typical application of the invention. In practice the details of the circuits may be varied and various refinements may be embodied in the system, for example, the relay R may be a standard form of releasing relay embodying means whereby the windings are automatically de-energized when the relay is released. In fact, in Fig. 1 of the drawings I have shown the exterior of a standard automatic releasing relay that I have used in carrying out the invention.

The releasing switch 15^a in the circuit through the control means C, heads 11, and timer T, may be incorporated in the relay R

so that this circuit is opened when the relay winding 51 is energized and the movable contact 41^a of the relay operated to open the motor circuit. For purpose of illustration, I have shown a switch 15 having a movable contact 90 normally in engagement with a stationary contact 91. Connection 15 extends to contact 90 while connection 15^b extends to contact 91. A trip contact actuator 92 is movable with the contact 41^a of the relay and operates to catch the contact 90 as the relay closes and lifts the contact 90 away from the contact 91 as the relay opens.

In practice I provide an alarm in connection with the apparatus adapted to operate when the timer is in action. In the circuit illustrated a relay 60 is connected between the connections 40 and 42 of the motor circuit so that an alarm device 62 is set into operation when the motor circuit is energized. The alarm device is shown connected in the motor M under control of the relay 60.

From the foregoing description it will be apparent that the invention provides apparatus which operates to automatically actuate or release the fire-extinguishing units one after the other or in succession and in a definite or predetermined timed relation. Further, it will be obvious how the apparatus operates to automatically cut out of operation after a predetermined operation.

Having described only a typical, preferred form of the invention, I do not wish to limit myself to the specific details set forth, but wish to reserve to myself any changes or variations that may appear to those skilled in the art or fall within the scope of the following claims:

Having described my invention, I claim:

1. In combination, an enclosure to be protected and from which gas has limited egress, a supply of fire-extinguishing gas, means responsive to a temperature corresponding to fire conditions in the enclosure for initially discharging a portion of the gas into the enclosure to establish a fire-extinguishing atmosphere therein, and means acting following operation of the first mentioned means to subsequently discharge other portions of the gas into the enclosure at predetermined intervals of time so that a fire-extinguishing atmosphere is maintained in the enclosure.

2. In combination, an enclosure to be protected and from which gas has limited egress, a plurality of containers carrying fire-extinguishing gas, means responsive to a temperature corresponding to fire conditions in the enclosure for releasing an amount of the gas into the enclosure to establish a fire-extinguishing atmosphere therein, and a control for subsequently releasing gas from the containers into the enclosure at spaced intervals of time relative to the time of operation of the first mentioned means to maintain a fire-extinguishing atmosphere in the enclosure.

3. In combination, an enclosure to be protected and from which gas has limited egress, a supply of fire-extinguishing gas, means for discharging an initial charge of said gas into the enclosure to establish a fire-extinguishing atmosphere, and control means for controlling the discharge of subsequent discharges of said gas into the enclosure including a timer for the control means put into operation upon the first mentioned means being actuated so that the subsequent charges are controlled to enter the enclosure at predetermined time intervals following the discharge of the initial charge into the enclosure.
4. In combination, an enclosure to be protected and from which gas has limited egress, a plurality of containers of fire-extinguishing gas, electrically controlled means in connection with the containers controlling the discharge of gas from the containers to the enclosure, and an electrical control for said means whereby an initial charge of gas is discharged into the enclosure to establish a fire-extinguishing atmosphere and a subsequent charge is discharged into the enclosure at a predetermined time after the initial charge to maintain a fire-extinguishing atmosphere in the enclosure.
5. In combination, an enclosure to be protected and from which gas has limited egress, a plurality of containers of fire-extinguishing gas, electrically controlled means in connection with the containers controlling the discharge of gas from the containers to the enclosure, and an electrical control for said means whereby an initial charge of gas is discharged into the enclosure to establish a fire-extinguishing atmosphere and a subsequent charge is discharged into the enclosure at a predetermined time after the initial charge to maintain a fire-extinguishing atmosphere in the enclosure, the electrical control including a timer.
- 45 In witness that I claim the foregoing I have hereunto subscribed my name this 25th day of February, 1929.

MAYNARD A. LASWELL.
